METHOD OF AND APPARATUS FOR INITIATING METAL-REMOVING OPERATIONS

John A. Rea, Shaker Heights, Ohio, assignor to
The Linde Air Products Company, a corpora-
tion of Ohio

Application May 31, 1940, Serial No. 338,199

10 Claims. (Cl. 148—9)

This invention relates to metal-removing operations, and more particularly to methods of and apparatus for heating a starting zone on a body of ferrous metal to prepare such a zone for the application thereto of cutting, descaling, or de-surfacing jets of oxidizing gas.

It has been customary when performing metal-removing operations with oxidizing gas to locate the nozzle of the metal-removing blowpipe closely adjacent to the starting zone on the body of metal and to apply preheating jets of combustible gas on or adjacent to the place where the metal-removing reaction is to begin in order to heat at least a portion of such starting zone to or above the ignition temperature. Such preheating jets may be produced by preheat orifices in the nozzle or by nozzle means disposed adjacent to the metal-removing nozzle. However, under certain circumstances it may be inexpedient to locate either the metal-removing nozzle or the preheating jets in close proximity to the starting zone; for example, where a plurality of separate metal-removing blowpipes are intended to operate on the metal body it may not be possible to locate them all adjacent to the starting zone; also where a single blowpipe is tilted with respect to the body, the position of the metal-removing blowpipe means may interfere with the progressive feeding motion of the body of metal. The present invention has for its purpose the provision of means whereby the metal-removing blowpipe means may be located in any desired position, even though at a point remote from the starting zone on the body of metal, and the preheating operation is accomplished by a separate oxidizing starting jet or stream (hereinafter referred to as "jet"), applied against a preheated portion of the metal body and directed so as to provide an incandescent area or a molten puddle at the starting zone against which the metal-removing stream or jet (hereinafter referred to as "stream") is applied.

The principal objects of the present invention are to provide improved methods of and apparatus for facilitating the starting of a thermo-chemical metal-removing operation by preheating to the ignition temperature a starting zone on a body of ferrous metal; to provide such method of and apparatus for removing metal employing the heat of combustion of a portion of the metal with an oxidizing starting jet for forming an incandescent area at the starting zone of the metal-removing operation; to provide a method of and apparatus for raising to the ignition temperature a portion of a metal body against which a metal-removing oxidizing gas stream is to be applied by preheating means positioned at a substantial distance from the initial zone of application of the metal-removing stream; to provide a method of and apparatus for rapidly severing a relatively

thick ferrous metal body by a metal-removing oxidizing gas stream applied to said body at an oblique angle to an upper surface thereof and facilitating the starting of such severing operation at a starting zone adjacent the bottom portion of the forward edge of said body by heating said zone to the ignition temperature by the application of preheating means and an oxidizing gas starting jet to the upper portion of said edge surface and directing said starting jet toward the starting zone to project molten metal and slag along such zone; to provide preheating methods and apparatus wherein a starting blowpipe preheats the top portion of the forward edge of a metal plate and projects a flame-cutting jet downwardly along such forward edge in the plane of the desired cut, to preheat a starting zone at the bottom of the forward edge; and to provide methods of and apparatus for controlling the flow of gases to the respective blowpipes and for co-ordinating with the operation of the blowpipes the progressive movement of the metal body relative to the blowpipes.

These and other objects will become more apparent from the following description and from the accompanying drawing.

In the drawing,

Fig. 1 is a perspective semi-diagrammatic view of a metal-removing blowpipe apparatus incorporating principles of the present invention and showing starting, cutting, and trimming blowpipes in operative relation to a body of ferrous metal; and

Figs. 2, 3, and 4, are diagrammatic views of the apparatus disclosed in Fig. 1, representing the relation of the blowpipes to the metal body during successive stages of operation.

Generally speaking, the invention comprehends facilitating the start of a metal-removing operation by projecting a starting jet of oxidizing cutting gas along a surface of a metal body so as to form in the body a substantially incandescent groove, path, or strip traversing the zone at which the metal-removing operation is to be started. The starting jet is projected from a starting blowpipe, preferably comprising a conventional cutting blowpipe having a nozzle provided with a central cutting oxygen orifice, and one or more adjoining preheating gas orifices. The starting blowpipe is located with its nozzle adjacent to the body of ferrous metal at a portion substantially remote from the zone of initial application of the metal-removing stream, so that the preheating jets from the nozzle may heat the remote portion to the ignition temperature in the usual manner. The starting jet of oxidizing gas when applied to the properly preheated remote portion, forms a starting channel or groove in the surface of the ferrous metal body extending from the remote portion to the starting zone.

The starting channel is rendered substantially incandescent by the molten products of the oxidation reaction occurring between the starting jet and the narrow strip of the ferrous metal body removed thereby.

The improved method of starting is applicable to all forms of thermo-chemical metal-removing operations such as flame-cutting or severing, flame grooving, or desurfacing, the starting zone being quickly and efficiently heated to above the ignition temperature by the exothermic heat liberated by the oxidizing action of the starting jet on a portion of the body operated upon. The starting jet of oxidizing gas may be projected in any suitable direction, for example, along a vertical or horizontal surface of the body of ferrous metal, provided of course, that the groove formed by the starting jet traverses the starting zone or portion sufficiently close to the starting zone as to produce the desired preheating effect. The metal-removing stream preferably is applied directly against the molten reaction products at any point along the starting groove, or against an adjoining portion of the metal body that is heated by the molten products within the groove sufficiently to react with the metal-removing stream.

One form of apparatus embodying the invention, as disclosed in Fig. 1, comprises a body of ferrous metal M such as iron or steel mounted in any suitable manner upon conveyor rollers 11 having a drive shaft 12 which may be rotated in a counter-clockwise direction, as by means of a drive motor (not shown), to propel the body of metal M forwardly in the direction of the arrow during the metal-removing operation. A main metal-removing blowpipe such as a grooving, cutting, or desurfacing blowpipe C is located so as to project a metal-removing oxidizing stream 13 against successive portions of the body of metal M along the desired path of travel. For purposes of illustration, the metal-removing blowpipe is herein disclosed and described as a cutting blowpipe, adapted to form a severing kerf K in the metal body M, extending from a starting zone 14 along the desired path as the blowpipe and body are moved relatively to one another, it being obvious that the body M could, if desired, be stationarily supported and the blowpipe moved relatively to the body by suitable means such as a cutting machine.

The starting zone 14 is heated to the ignition temperature by means of a separate oxidizing gas jet issuing from a starting blowpipe S and directed toward the starting zone 14 so as to form a molten puddle at or adjacent to the starting zone as a result of an oxidation reaction effected between the flame-cutting starting jet and portions of the ferrous metal adjacent to the starting zone. The oxidizing jet projected from the starting blowpipe S may be of relatively low velocity, such as is employed in performing a de-seaming or grooving operation, or of high-velocity as employed in conventional flame-cutting operations. As shown in Fig. 1 the starting blowpipe S is located so that the discharge portion of the nozzle 15 is closely adjacent to the surface against which the metal-removing stream 13 is to be applied but substantially remote from the starting zone 14. For example, where the starting zone 14 is located on a forward edge face 16 of the body M, the nozzle 15 may be located so as to project its preheating flames and starting jet against or along the same face 16. If the starting jet is aligned with the plane of the pro-

posed cut or kerf K it assists in preheating the body of metal M along the path to be followed by the cutting stream 13; also, when the starting jet is thus aligned, the starting groove merges with and is included within the kerf, and therefore does not deface the work.

In the arrangement shown in Fig. 1, the cutting blowpipe C is preferably adjustably mounted with respect to the starting blowpipe S as by 10 means of a supporting clamp 17 or other suitable supporting means capable of sustaining both blowpipes above the body M, and which permits adjusting the spacing and the angle of inclination between the respective blowpipes. The cutting blowpipe C is located so that its nozzle 18 is inclined forwardly in the direction of its travel relative to the body M. By the use of a forwardly inclined cutting stream 13 the flame-severing operation may be performed at a higher rate of 20 speed than otherwise, as fully explained in Patent 2,184,561 dated December 26, 1939. Both blowpipes C and S are located with the discharge portions of the nozzles 15 and 18 adjacent to but slightly above the level of the top surface 19 of the body of metal M so as not to interfere with the body M as it is moved forwardly in the direction of the arrow during the cutting operation. With the blowpipes S and C arranged as shown in Fig. 1, the zone of initial application 14 of the cutting stream 13 is located at the bottom of the forward edge surface 16, and the nozzle 18 is separated from the starting zone by such an excessive distance that the preheating jets from the nozzle 18 are of insufficient intensity to independently preheat the starting zone 14 to the ignition temperature.

The starting blowpipe S is located apart from the blowpipe C and initially is positioned so that it may project preheating flames against the top 30 of the edge 16, to preheat a small area or portion 10 thereof to or above the ignition temperature. The nozzle 15 is positioned to project the starting jet of oxidizing gas against the preheated top portion 10, and thence vertically 40 downward along the edge surface 16 in the plane of the desired cut, thereby forming a groove or channel 21 in the edge surface 16, along which channel are projected the molten products of the exothermic reaction between the starting jet and the vertical strip of metal removed by the starting jet. The blowpipes S and C are illustrated as being aligned in the plane of the kerf so that the channel or groove 21 traverses the starting zone 14 and preheats that zone sufficiently to receive the stream 13.

The oxygen and acetylene connections to the respective blowpipes and the means employed to control the flow of gases are diagrammatically illustrated in Fig. 1. Tubes 22 and 23 conduct fuel gas such as acetylene and a combustion-supporting gas such as oxygen from respective sources of supply to the preheating gas mixture chambers of the blowpipes S and C. Cutting oxygen for both blowpipes S and C passes through a main supply tube 24 to a two-way valve 25, operable by means of a lever 26 to connect the main cutting-oxygen supply tube 24 with either of the cutting oxygen tubes 27 or 28. Two separate valves may be employed in place of valve 25, in the event that it is desired to have the starting jet continue briefly after the metal-removing stream is turned on. Preheating mixture valves 29 and 31 regulate the flow of the preheating oxygen and acetylene to the respective blowpipes.

A switch 32 or similar control means is employed for actuating the means that provides relative movement between the body of metal M and the cutting blowpipe C. The switch 32 may be provided with electrical connections adapted to open or close the circuit to the conveyor motor (not shown); by connecting the switch to the lever 26 in the manner shown in Fig. 1, the operation of the conveyor motor may be suitably coordinated with the operation of the cutting blowpipe C, as will be more fully explained.

Although a forwardly inclined cutting blowpipe may provide higher cutting speeds, the edges or sides of the kerf formed by such a blowpipe may be more irregular than those formed by a blowpipe progressing at lower velocities. Such irregularities in the kerf wall may be corrected by means of a trimming blowpipe which follows at a distance behind the cutting blowpipe, slightly to one side of the central plane of the kerf K so as to project an oxidizing trimming jet or stream against one of the irregular walls thereof. The function and operation of such a trimming jet has been fully described in Patent 2,184,561 dated December 26, 1939. A trimming blowpipe T may be secured in spaced relation to the cutting blowpipe C in any desired manner as by means of the supporting clamp 17. The blowpipe T is supplied with preheating acetylene and oxygen by connection with the tubes 22 and 23, and with cutting oxygen by connection with the cutting oxygen tube 27. The flow of all gases to the trimming blowpipe T is controlled by a tandem-operated valve 33 which allows the blowpipe T to be rendered operable or inoperable at will.

The nature of the invention may be more fully understood in connection with a typical example of operation. In accordance with the arrangement shown in Fig. 1, a body of metal M is located upon the conveyor rollers 11 with the forward edge 16 of the body facing the cutting blowpipe C. The starting blowpipe S is positioned adjacent to the forward edge 16 so that the preheating flames from the nozzle 15 may preheat to the ignition temperature the small portion 10 at the top of the edge 16, preferably in the plane of the desired cut, and so that the starting jet, when projected from the nozzle 15, will intercept the edge 16 sufficiently to form a groove or channel extending downwardly along the forward edge toward and into juxtaposed relation with the starting zone 14. The cutting blowpipe C meanwhile is spaced forwardly from the forward edge 16 with the nozzle 18 inclined forwardly in the direction of its travel relative to the body M so that the bore of the nozzle 18 may project the cutting stream 13 in the plane of the desired cut at the beginning of the path of travel, that is, the starting zone 14. The trimming blowpipe T may be positioned as shown behind the cutting blowpipe C, if desired.

In starting a cut, the valves 29 and 31 are adjusted to allow the passage of the proper proportion of preheating gases to the blowpipes, the valve lever 26 being located in a vertical position to shut off the supply of cutting oxygen. The preheating flames of the cutting blowpipe C, though remotely positioned from the starting zone 14, contribute in some measure to the preheating action of that area, but ordinarily are incapable of independently raising the starting zone to the ignition temperature within a reasonable time. The preheating flames of the starting blowpipe S, though remotely positioned

from the starting zone 14 and from the cutting blowpipe C, are effective to quickly preheat the portion 10. At the moment that the area 10 beneath the nozzle 15 has been raised to the ignition temperature, the valve lever 26 is moved in a clockwise direction so as to connect the tube 28 with the cutting oxygen supply tube 24 thereby by projecting the starting jet from the nozzle 15 and producing the groove or channel 21 in the edge 16. The brief oxidation reaction of the starting jet heats the entire strip of metal along the channel 21 to a high temperature thereby preheating the area 14 to receive the severing or metal-removing stream 13. Without delay, the lever 26 is shifted in a counter-clockwise direction to the position shown in Fig. 1, thereby discontinuing the starting jet and connecting the cutting-oxygen tube 27 of the blowpipe C with the supply tube 24. The stream 13 impinges on and reacts with the heated metal at the starting zone 14 to start the cut. The conveyor rollers can be set in motion at the time that the cutting operation is inaugurated to move the body M forwardly, causing the stream 13 to be applied to successive portions of the body along the desired line of cut. The control element of the conveyor motor switch 32 may be connected with the lever 26 so that when the lever 26 is moved to the position indicated in Fig. 1, the circuit to the conveyor motor is completed.

The arrangement shown in Fig. 1 illustrates the relation of the parts at the moment following the discontinuance of the starting jet and initiation of the flow of the stream 13. Figs. 2, 3, and 4 illustrate diagrammatically successive positions of the blowpipes with respect to the work M. In Fig. 2 the starting blowpipe S has been rendered completely inactive by closing the preheating mixture valves 29. The cut meanwhile has progressed upwardly and forwardly along the desired path, the cut being maintained by the combined heating effect of the starting jet, the preheating jets of the cutting blowpipe C, and the exothermic heat of the cutting reaction. In Fig. 3 the cut has progressed to the top surface 19 and the preheat is supplied principally by the preheating jets of the cutting blowpipe C which in this position are located adjacent to the surface 19. If desired, the trimming blowpipe T may be placed in operation by manipulating the tandem-operated valve 33 which turns on the preheating and cutting gases. The trimming jet of oxidizing gas from the blowpipe T follows along the kerf K behind the blowpipe C to trim at least one of the walls of the kerf. If the trimming blowpipe T is located sufficiently close to the cutting blowpipe C no additional preheating means will be required as the residual heat from the preceding operations and the heat provided by the preheating jets of the trimming blowpipe are ordinarily sufficient to maintain the wall of the kerf at the ignition temperature to receive the trimming jet. Fig. 4 is a view similar to Fig. 3 but discloses the cutting and trimming blowpipes in a more advanced position along the desired line of cut as the body M is moved by the rollers 11 in the direction of the arrow.

Although the starting blowpipe S has been described as preferably projecting the starting jet downwardly along the forward edge surface, it is obvious that it may be projected along different surfaces, for example, horizontally along the bottom surface of the body M toward the starting zone 14. Obviously, the blowpipes S, C,

2,388,020
and T may be mounted so as to be moved along the desired path of travel relatively to a stationary body of metal. The invention is not limited to flame-severing or similar flame-cutting operations but is applicable generally in facilitating the start of other similar thermo-chemical reactions.

Various modifications of the herein disclosed method and apparatus may be made by those skilled in the art without departing from the principles of the invention or sacrificing its advantages.

I claim:

1. A method of initiating the oxidation reaction between a ferrous metal body and an oxidizing cutting gas stream adapted to be applied to successive portions of said body, said stream being inclined forwardly in the direction of travel, said method comprising projecting a flame-cutting jet along the forward end edge of said body in alignment with the cut to be formed by said stream to form an incandescent groove along said edge; and discontinuing said jet and substantially simultaneously therewith projecting said cutting gas stream against said body adjacent to the zone at which said incandescent groove intersects the bottom of said forward end edge.

2. A method of flame-severing a ferrous metal body with a flame-severing stream projected from the bore of a nozzle against successive portions of said body, comprising positioning said nozzle above said body in the plane of the desired cut with the lower end of said nozzle inclined forwardly in the direction of travel of said nozzle relative to said body; spacing said nozzle from the forward end edge of said body until said bore is aligned with a zone at the bottom of said edge; projecting a flame-cutting jet downwardly along said forward end edge in the plane of the severing cut, whereby said jet forms an incandescent strip of metal along said edge traversing said zone; applying said flame-severing stream from said nozzle against said zone; and moving said nozzle in a generally horizontal path relative to said body along the line of the desired severing cut.

3. Method as claimed in claim 2 wherein said jet is discontinued substantially at the time said flame-severing stream is applied.

4. Flame-cutting apparatus comprising a flame-severing blowpipe having a nozzle adapted to project a flame-severing stream against a ferrous metal body; means for providing relative motion between said blowpipe and said body whereby said stream may be projected against successive portions of said body; and a flame-cutting starting blowpipe having a nozzle adapted to project preheating and oxidizing cutting jets against said body, said respective blowpipes being so arranged that at the start of a starting operation said cutting blowpipe is adapted to preheat the top of said body at the forward edge thereof and to apply a cutting jet downwardly against the preheated portion and along said forward edge in the plane of the desired cut to form an incandescent starting groove in said forward edge, and said flame-severing blowpipe is spaced from said forward edge and inclined in the plane of the desired cut so as to project said severing jet against the bottom of said forward edge in the region traversed by said incandescent groove.

5. Flame-cutting apparatus as claimed in claim 4 wherein both of said nozzles are located so

that the discharge portions thereof are at an elevation slightly above the top surface of said body.

6. A method of starting the cutting of a substantially horizontal ferrous metal body having a substantially vertical end face, with a downwardly directed stream of oxidizing gas inclined with respect to said face and adapted to move horizontally relatively to said body to form a cut in a substantially vertical plane passing through said end face whereby said stream initially impinges against a zone at the bottom edge of said face, which method comprises causing molten material to run down said face substantially in said vertical plane to start the cutting operation of said stream in said zone at the bottom edge of said face, and then advancing said stream with respect to said body so that said face is cut upwardly along the vertical path of said molten material.

7. Blowpipe apparatus comprising a substantially vertical starting blowpipe nozzle, an inclined cutting blowpipe nozzle, means supporting said nozzles with their longitudinal axes converging in a substantially vertical plane so as to intersect adjacent to the surface of a work body, and means including a two-way valve for supplying cutting oxygen to said nozzles so that said oxygen may be supplied to either one but not both of said nozzles at the same time.

8. In a method of performing a main metal-removing operation by applying a main metal-removing stream of oxidizing gas to successive portions of a surface of a ferrous metal body along a path beginning at a zone on said surface, the improvement which comprises quickly heating said zone for thermo-chemical reaction with said stream, by projecting a separate flame-cutting starting jet toward said zone along said surface from an edge of said body bordering on said surface to react exothermally with surface portions of said body, said jet thereby forming an incandescent strip extending from said edge to said zone, said incandescent strip being adapted to react with said main metal-removing stream of oxidizing gas at said zone to start said main metal-removing operation.

9. In a method of performing a main metal-removing operation, the improvement as set forth in claim 8 including the step of discontinuing said starting jet substantially upon the application of said main metal-removing stream to said zone.

10. In a method of performing a main metal-removing operation by applying a main metal-removing stream of oxidizing gas to successive portions of a surface of a ferrous metal body along a path beginning at a zone on said surface, the improvement which comprises quickly heating said zone for thermo-chemical reaction with said stream, by projecting a separate flame-cutting starting jet toward said zone along said surface from an edge of said body bordering on said surface to react exothermally with surface portions of said body, said jet thereby flame-cutting in said surface an incandescent groove included within said path and extending from said edge to said zone, said incandescent groove being adapted to react with said main metal-removing stream of oxidizing gas at said zone to start said main metal-removing operation; and discontinuing said starting jet substantially upon the application of said main metal-removing stream to said zone.

JOHN A. REA.
